(57) **CLAIM**

The ornamental design for a display screen or portion
thereof with animated graphical user interface, as shown and
described.

DESCRIPTION

FIG. 1 is a front view of a display screen or portion thereof
with animated graphical user interface, showing a first
image of the claimed design;

FIG. 2 is a second image thereof;

FIG. 3 is a third image thereof; and,

FIG. 4 is a fourth image thereof.

The broken lines in the figures show a display screen or
portion thereof and form no part of the claimed design.
The appearance of the animated image sequentially
transitions between the images shown in FIGS. 1-4. The process
or period in which one image transitions to another forms no
part of the claimed design.
